UNITED STATES PATENT OFFICE.

ADOLPH G. BAUER, OF WHITEWATER, COLORADO.

MINING-CAR.

1,325,609.

Specification of Letters Patent. Patented Dec. 23, 1919.

Application filed August 10, 1917. Serial No. 185,604.

To all whom it may concern:

Be it known that I, ADOLPH G. BAUER, a citizen of the United States, residing at Whitewater, in the county of Mesa, State 5 of Colorado, have invented certain new and useful Improvements in Mining-Cars; and I do hereby declare the following to be a full, clear, and exact description of the invention, such as will enable others skilled 10 in the art to which it appertains to make and use the same.

This invention is an improvement in mining cars and has for one of its objects to provide an improved car a portion of which 15 may be placed within a tunnel previous to a blast in such manner that the same will cover the bottom of the tunnel so that the muck will fall into the cars when the blast is shot.

20 The inventive idea involved is capable of receiving a variety of mechanical expressions, one of which, for the purpose of illustrating the invention, is shown in the accompanying drawing, wherein:—

25 Figure 1 is a longitudinal section through one of the cars and truck therefor constructed in accordance with the invention.

Fig. 2 is an end elevation of one of the cars and a portion of the truck.

30 Fig. 3 is a central transverse section of one of the cars through the pivot.

Fig. 4 is an elevation looking at the other end of the car from that shown in Fig. 2.

35 Fig. 5 is a horizontal sectional view of the lock for retaining the hinged end of the car in vertical position.

Referring to the drawings, the numeral 11 indicates a truck of any preferred construction having the wheels 12, said truck 40 being employed for the purpose of conveying the cars to and from the tunnel before and after the blast and being preferably mounted on the tracks 13. The truck is provided centrally thereof with a turn-table 45 construction consisting of a relatively stationary base member 14 having rotatably mounted thereon a bearing 15 extending transversely of the truck and provided with the upstanding ends 16 in which is mounted a pivot member 17. Rotatably mounted about the pivot 17 is a bearing 18 which supports a cradle consisting of a transversely extending base 19 and upturned ends 20 between which a car body, generally indicated by the numeral 21, is adapted to be mounted whereby the same may be con-

veyed to and from a tunnel and tilted by reason of the pivot 17 so as to dump the contents thereof.

The cradle is received between the transverse strips 17' secured to the under side of the body bottom and spaced apart a distance greater than the width of the cradle. This wide spacing of the strips permits the rough placing of the body in the cradle 65 after which it is slid along until the strip 17' at one side strikes the cradle, the latch mechanism when engaged serving to prevent sliding movement of the body on the cradle in the opposite direction.

70 The car body preferably comprises a bottom 22 having the sides 23 hinged thereto at 24. When the car body is mounted in the cradle 19 the sides are supported in their vertical positions by means of the end sections 20 and in order to further support said sides the same are provided at their upper edges with the hooks 25 engaged by chain sections 26 extending transversely of the top of the car and connected by the turn-buckle 80 27 which may be operated to draw the sides inwardly and thus securely maintain the same in their upright positions. The bottom 22 also has pivoted in one end thereof, as indicated at 28 the hinged end 29 of the 85 car which is maintained in its upright position by the construction illustrated in Fig. 5 wherein it will be seen that the end is provided with an angle iron 30 to which is secured a bracket 31 forming an opening 32 90 for receiving one end of a locking bolt 33, the outer end of which is hooked around the bar 34 carried by the adjacent side 23 of the body and extending through said outer end of the bolt 33 and the bar 34 is a locking pin 95 35 carried by a small chain 36 secured to said side 23. It will be apparent that by removing the pin 35 the locking bolt 33 may be extracted from its locking position and the end 29 swung about its pivot. The car 100 is further provided with a removable or detachable end 37 having a handle 38. The upper portion of the end 37 is provided with plates 37' from which project fingers 38' that engage with cleats 39' on the sides 105 of the car body. The end 37 may be raised off of these cleats when it is desired to remove the end from the car body, but when the end is in use it rests between the corresponding edges of the car sides 23. The 110 lower edge of the end 37 is provided with keepers consisting of angle plates as illus-

trated in Fig. 4, each having one extremity 40' secured against the outer face of the end 37 and the other extremity 41 hooked and spaced from the face of the end. These 5 hooks 41 receive behind them latch fingers 39 which are pivoted at their lower ends as shown at 40. When these fingers are in vertical position as illustrated in Fig. 4, they serve to engage the keepers and hold the 10 lower edge of the end 37 against movement either inwardly or outwardly of the car body, but when they are swung downwardly and out of position the end 37 is released at its lower edge portion.

15 In order to maintain the body of the car in a substantially horizontal position so that the same will not tilt about the pivot 17 when it is not desired to dump the contents of the car, the truck 11 has pivoted 20 thereto at 42 adjacent the hinged end 29, a latch 43 having an inturned end 44 adapted for engagement with a keeper 45 secured to the bottom 22, said latch being actuated to its operative and inoperative positions 25 by means of a lever 46 also mounted upon the pivot 42 and connected to the latch by a brace 47. When the extension 44 is in engagement with the catch 45 it will be apparent that the car will be held in a horizontal position. By lifting the lever 46 said 30 extension 44 may be disengaged whereupon the car will be free to swing about the pivot 17 and by removing the end 37 of the car it will be apparent that the contents there- 35 of may be readily dumped.

What is claimed is:—

1. A mining car comprising a body including a bottom having a plain unobstructed upper surface, sides hinged at the longitudinal edges of the bottom, an end 40 removably connected to one end of the bottom and to the sides, an end hinged to the other end of the bottom and movable to stand between the sides when the latter are in erect positions, and means for holding the last named 45 end erect.

2. A mining car comprising a body portion including a bottom, sides hinged thereto, a removable end, a hinged end connected to said bottom and adapted to stand between 50 the sides when said end and sides are in erect positions, and a cradle in which the body is removably received.

3. A mining car comprising a body portion including a bottom, sides hinged thereto, a removable end, a hinged end connected to said bottom, flexible means connecting said sides whereby to releasably maintain the same in vertical closing positions, means for detachably securing the upper portion of 55 the removable end to the sides and means for removably connecting the lower portion of the last named end with the bottom.

In testimony whereof, I affix my signature in the presence of two witnesses.

ADOLF G. BAUER.
